SYRINGE

Vincent L. Vaillancourt, Livingston, N.J., assignor to
C. R. Bard, Inc., Murray Hill, N.J., a corporation of
New York

Filed Jan. 16, 1969, Ser. No. 15,376

Term of patent 14 years

Int. Cl. D24—03; D7—02

U.S. Cl. D83—1

FIG. 1 is an elevational view of a syringe embodying my new design;

FIG. 2 is an elevational view of the syringe with parts partially broken away to show the cross-sectional characteristics thereof.

FIG. 3 is an end view from the bottom of FIG. 1.

The characteristic features of my design reside in the specific configuration of the syringe bulb member, as best illustrated in FIG. 2 of the drawing.

I claim:

The ornamental design for a syringe, substantially as shown and described.
